UNITED STATES PATENT OFFICE.

HAL R. FULK, OF MULVANE, KANSAS.

GREASE GUN.

Application filed June 21, 1928. Serial No. 287,131.

This invention relates to new and useful improvements in grease guns and aims to provide a device of this character wherein oil or grease may be injected into various parts of an automobile under air pressure and under the action of a manually controlled pump mechanism which in the present device need not be brought into play unless the pressure of the air within the grease container is insufficient to force the oil or grease into the part being lubricated.

One of the most important objects of this invention is to provide a grease gun of this character that is of extremely simple construction and inexpensive of manufacture as well as efficient in use the same embodying but few parts and these so correlated as to reduce the possibility of disarrangement to a minimum.

With the foregoing and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the several views:

Figure 1 is a side elevation of my improved grease gun the lower end of the grease container being illustrated in cross section.

Figure 2 is a top plan view thereof, and Figure 3 is a detail longitudinal section through the hand pump mechanism of the gun.

Now having particular reference to the drawings my novel invention consists of an oil or grease container 5 of suitable capacity provided at its bottom wall with a threaded opening within which is normally arranged a plug 6 which when removed will permit the container to be filled. Within the top wall of this container is a suitable air inlet valve 7 whereby air under pressure may be injected into the container for normally tending to discharge the same through a vertical discharge pipe 8 having communication with the container adjacent its lower end. Within the upper end of this pipe 8 is located a suitable valve 9 while communicating with this valve is an oil or grease chamber 10 having a lateral discharge port 11 with which is associated an upwardly extending discharge pipe 12 to the upper

end of which is attached a flexible hose 13 having a suitable fitting 14 upon its outer end to facilitate the attachment of the hose to the various oil and grease receiving fittings of an automobile. Extending vertically from the chamber 12 and having communication therewith is a narrow bore and elongated cylinder 15 within which is rectilinearly movable a plunger rod 16 which extends above the cylinder 15 as disclosed the upper end of this cylinder being provided around the rod with a suitable packing 17. Within the lower end of the chamber 10 is a suitable upwardly opening check valve 10'.

Pivotal secured at its inner end to a suitable fitting 18 associated with the upper end of the container 5 is a handle lever 19 preferably composed of a single length of metal bent intermediate its ends to provide a pair of spaced legs as disclosed. Loosely mounted within a transverse sleeve 20 at the upper end of the plunger 16 is a depending yoke 21 the lower ends of the legs of which are loosely arranged within the side legs of said handle lever 19, (see Figure 3). Obviously when the oil or grease within the container 5 is under pressure and the fitting 14 of the hose 13 arranged upon a grease receiving fitting of an automobile or other mechanism and the valve 9 opened the oil or grease will be forced from the container into the machine fitting. However, in the event the pressure within the container 5 falls below the required degree to forcibly eject the material from the container and into the machine fitting a reciprocation of the handle lever 19 will cause the actuation of the plunger rod 16 for sucking the material from the container and thence projecting the same through said hose.

In view of the foregoing description when considered in conjunction with the accompanying drawings, it will be apparent that I have provided a novel, simple and highly useful grease gun that is well adapted for all of the purposes heretofore designated and even though I have herein shown and described the invention as consisting of certain detail structural elements it is nevertheless to be understood that some changes may be made therein without affecting the spirit and scope of the appended claims.

Having thus described my invention, what is claimed as new is:

1. In a grease gun of the character de-

scribed, a grease container, means whereby air under pressure may be injected into the container above the level of the grease, a discharge pipe communicating with the lower 5 end of the container and having a control valve therein, a chamber communicating with the upper end of the pipe and having a lateral nipple for facilitating the attachment of a discharge hose thereto, a narrow 10 bore cylinder communicating with the upper end of the chamber, a plunger rod reciprocatorily mounted within said cylinder, a yoke loosely pivoted to the upper end of the plunger and depending therefrom, a handle 15 lever pivoted at its inner end to the upper end of the container and loosely connected to the lower ends of the legs of said yoke all in a manner and for the purpose described.

2. In a grease gun of the class described, 20 a grease container, means whereby air under pressure may be projected into the container above the level of the grease, a discharge pipe communicating with the lower end of the container and having a control valve 25 therein, a chamber communicating with the upper end of the discharge pipe, a discharge

hose for connection to the side of the chamber, a cylinder having communication at its lower end with the upper end of the chamber, a plunger rod arranged for reciprocatory movement in the cylinder and in said chamber, an upwardly opening check valve arranged within the chamber below the connection with the discharge hose, a transverse sleeve carried by the upper end of the plunger rod, a yoke having its crown portion journaled in said sleeve, the arms of the yoke being disposed downwardly, the free ends of the arms being directed inwardly, a pair of handle forming bars pivotally connected 35 at their inner ends to the top of the container, said bars being disposed on opposite sides of the upper end portion of the plunger rod, the intermediate portions of the bars being formed with openings to accommodate 40 the inwardly directed ends of the respective arms of the yoke to operatively connect the bars with the plunger rod, the outer ends of the bars being connected together to provide 45 a handle.

In testimony whereof I affix my signature.
HAL R. FULK.
